Primary Examiner — Rachel A. Voorhies

Assistant Examiner — Benjamin D. Wannemacher

(57) **CLAIM**

The ornamental design for a tool for skateboards, as shown and described.

DESCRIPTION

FIG. 1 is a perspective view of a tool for skateboards showing our new design;
FIG. 2 is a front view thereof;
FIG. 3 is a rear view thereof;
FIG. 4 is a left view thereof;
FIG. 5 is a right view thereof;
FIG. 6 is a top view thereof;
FIG. 7 is a bottom view thereof;
FIG. 8 is an exploded perspective view thereof; and,
FIG. 9 is a perspective view of the tool for skateboards in use.
The broken lines are for the purpose of illustrating portions of the tool for skateboards and form no part of the claimed design.

1 Claim, 8 Drawing Sheets(56)
